UNITED STATES PATENT OFFICE

114,366

DESIGN FOR A JACKET FOR TOBACCO
CONTAINERS

Clayton T. Hobba, Los Angeles, Calif., assignor to Larus & Brother Company, Inc., Richmond, Va., a corporation of Virginia

Application March 1, 1939, Serial No. 83,285

Term of patent 14 years

To all whom it may concern:

Be it known that I, Clayton T. Hobba, a citizen of the United States, residing at Los Angeles, in the county of Los Angeles and State of California, have invented a certain new, original, and ornamental Design for a Jacket for Tobacco Containers, of which the following is a specification, reference being had to the accompanying drawing, forming part thereof.

Fig. 1 is a top perspective view of a jacket for tobacco containers showing my new design;

Fig. 2 is a rear elevation.

I claim:

The ornamental design for a jacket for tobacco containers, as shown.

CLAYTON T. HOBBA.
